L. WILKE

THEFTPROOF RECEIVER BOX

Filed Feb. 24, 1923

By his Attorneys
Inventor
Louis Wilke
Edgar Dato & Co.

UNITED STATES PATENT OFFICE.

LOUIS WILKE, OF MORSEMORE, NEW JERSEY.

THEFTPROOF RECEIVER BOX.

Application filed February 24, 1923. Serial No. 620,903.

To all whom it may concern:

Be it known that I, LOUIS WILKE, a citizen of the United States, and residing at Morsemere, in the county of Bergen and 5 State of New Jersey, have invented certain new and useful Improvements in Theft-proof Receiver Boxes, of which the following is a specification, such as will enable those skilled in the art to which it appertains 10 to make and use the same.

This invention relates to receiver boxes particularly designed for household use and which are adapted to be placed in juxtaposition to the entrance to a house or apartment 15 and to be automatically locked by a member or members engaging the door, or co-operating with the door and the door frame-work, said receiver box being adapted to receive articles delivered to the house or apartment 20 such for example as bottles of milk, cream and the like, after which the closure member of such receiver box is moved into operative or locked position to prevent the removal of the articles placed in said receiver boxes 25 until the door is opened, and the object of the invention is to provide a keyless receiver box of the class described with one or more members adapted to be placed between the door and doorframe for retaining 30 the receiver box in juxtaposition thereto, one of said members forming a part of the lock mechanism of said receiver boxes, a further object being to provide means whereby the cover member of the receiver 35 box cannot be moved into a locked position until an article or articles have been placed in the receiver boxes, said means being automatically actuated and moved into inoperative position by the placement of an article 40 or articles in the receiver box, and with these and other objects in view, the invention consists in a device of the class and for the purpose specified, which is simple in construction, efficient in use and which is constructed as hereinafter described and 45 claimed.

The invention described and claimed herein is an improvement on that shown and described in a prior application for a 50 patent filed December 7, 1921, Ser. No. 520, 506, and is fully disclosed in the following specification of which the accompanying

drawing forms a part, in which the separate parts of my improvement are designated by suitable reference characters in each of the 55 views, and in which:—

Fig. 1 is a central longitudinal sectional view through my improved receiver box with the various parts thereof in an operative position.

Fig. 2 is a front view of the box shown in Fig. 1 with parts of the construction broken away and in section.

Fig. 3 is a plan view of the box shown in Fig. 1 with parts of the construction 65 broken away and in section; and,

Fig. 4 is a view similar to Fig. 1 but showing only a part of the construction and showing the parts in an inoperative position.

In practice I provide a receiver box or casing 10 which is oblong and rectangular in form and open at the top, the top of the box or casing being adapted to be closed by cover member 11, hinged as shown at 12 and one side wall 13 of the receiver box tapers upwardly and outwardly to reduce the transverse dimensions of the bottom of the receiver box as clearly shown in Fig. 1 of the drawing. Mounted transversely of the top of the receiver box adjacent to one corner thereof is a lock rod 14 provided centrally with an enlarged or offset portion 15 and at one end with a projecting lock member 16 preferably bent in the manner shown in Fig. 3 of the drawing, and the lock bar 14 may be inserted into the casing on the lock member 16 thereof at either side of the casing, and suitable means, for example a pinned collar 17, is provided for retaining the lock rod against displacement from the casing.

Another lock member 18 is similar to the lock member 16 and composed of a strip of sheet metal is adapted to be secured to either side of the box or casing by passing a projecting portion 19 thereof through an aperture in the casing and passing a pin 20 through the projection 19 as illustrated in Fig. 1 of the drawing, and in practice both of the lock members 16 and 18 are adapted to be placed between one side of a door 21 and the adjacent side of the doorframe 22 as indicated in dot and dash lines in Fig. 3 of the drawing, to retain the receiver box

against displacement when the door is in a closed position.

Secured to the opposite sides of the receiver box, adjacent to that part thereof 5 through which the lock rod 14 passes are substantially hook-shaped members 23 having spring members 24 which are adapted to retain and support the lock member 16 in a raised or operative position and also 10 to hold the offset portion 15 of the lock rod in a predetermined position.

Secured to the inner face of the cover member 11 is a pivoted spring-actuated dog 25 which is adapted to engage the offset portion 15 of the lock rod 14 to lock the cover member 11 in its closed position, and the top of the wall 13 of the receiver box in the construction shown is extended inwardly as shown at 26 and downwardly as shown 20 at 27 to form an enclosure for the lock mechanism of the receiver box or lock controlling mechanism, and the extension 26 is apertured as shown at 28 to permit of the passage of the dog 25 therethrough.

25 A suitable bail 29 is pivotally mounted in connection with studs 30 approximately centrally of the opposite sides of the receiver box and the studs are provided with inwardly projecting portions 31, on which are 30 pivotally mounted levers 32 adjacent to the inner faces of the side walls of the receiver box, and the levers 32 are joined at their upper ends by a substantially L-shaped 35 crosshead portion 33 which is adapted to cooperate with the lock rod 14 and principally the projecting portion 15 thereof, as shown in Fig. 4 of the drawing to prevent the dog 25 from engaging said lock rod. The lower ends of the levers 32 are provided with offset lip portions 34 and pivoted to the lower end portions of said levers are ears, a wire frame 35 which is substantially U-shaped in form and the bottom or cross-head portion 35 of which is fashioned in the manner indicated in full and dotted lines 40 in Fig. 3 of the drawing to form a support for a board member 36, upon which milk bottles or other articles are adapted to be placed.

50 The use of my improved box will be readily understood from the foregoing description when taken in connection with the accompanying drawing, and the following statement. It will be understood that the receiver box is first placed in and between a door and door frame in the manner diagrammatically illustrated in Fig. 3 of the drawing, and if the box be empty, the parts 55 will assume the position shown in Fig. 4 of the drawing, in which the crosshead 33 of the levers 32 is in engagement with the offset portion 15 of the lock rod 14 and in this position if the cover member 11 be moved 60 downwardly into a closed position, the

crosshead portion 33 will operate to prevent the engagement of the dog 25 with the lock bar 14 and it will be impossible to lock said cover member, as will be apparent. When an article, such for example as a milk bottle, 70 is placed in the receiver box however, and upon the board or platform 36, said board will be lowered, thus operating the levers 32 to move the same into the position shown in full lines in Fig. 1 of the drawing, to move the crosshead 33 out of engagement with the lock rod 14, and the operation of closing the cover member 11 will bring the dog 25 into engagement with the offset portion 15, and the cover member will 75 then be locked, and in order to reopen the receiver box, the door 21 must be first opened after which the lock member 16 may be rotated to move the offset portion 15 of the lock rod 14 into inoperative position to 80 permit the opening of the cover member 11, and in this operation, the spring member 24 supporting the lock member 16 is depressed by hand.

85 A receiver box of the class specified will 90 be as near as possible fool proof in its use, in that it is necessary to first place the articles to be delivered into the receiver box before the cover member can be moved into a locked position, and no education on the 95 part of the party delivering the packages to be placed in the receiver box will be required, and further the cover member of the receiver box cannot accidentally be locked without the placement of a package or packages therein and while I have shown certain details of construction for carrying my invention into effect, it will be understood that I am not necessarily limited to these details 100 and various changes therein and modifications thereof may be made within the scope of the appended claims without departing from the spirit of my invention or sacrificing its advantages.

105 It will also be understood that the levers 32, frame 35 and board 36 may be removed from the casing by springing the levers 32 inwardly toward each other to disengage 110 said levers from the projections 31. This will facilitate the cleaning of the interior 115 of the receiver box as well as the board 36 at will.

Having fully described my invention, what I claim as new and desire to secure by Letters Patent, is:—

120 1. A receiver box of the class described provided with members adapted to be placed between a swinging member and stationary support therefor, said members being reversible on the receiver box, and one of 125 which constitutes a part of a lock mechanism and extends transversely through the receiver box and the closure of the receiver box being provided with a catch device adapted to cooperate with said last named 130

member for retaining the closure in a closed position.

2. A receiver box of the class described provided with members adapted to be placed between a swinging member and stationary support therefor, said members being reversible on the receiver box, and one of which constitutes a part of a lock mechanism and extends transversely through the receiver box, the closure of the receiver box being provided with a catch device adapted to cooperate with said last named member for retaining the closure in a closed position, and means within said receiver box for controlling the engagement of said catch device with said member.

3. A receiver box of the class described provided with a closure having a catch device, a rod mounted transversely of the receiver box and in connection with which said catch device is adapted to operate, said rod projecting through one side of the receiver box and being provided with a bent lock member adapted to be placed between a swinging member and stationary support for retaining the receiver box in predetermined position, and a member movably mounted in the receiver box and normally cooperating with said rod to prevent the engagement of said catch device therewith.

4. A receiver box of the class described provided with a closure having a catch device, a rod mounted transversely of the receiver box and in connection with which said catch device is adapted to operate, said rod projecting through one side of the receiver box and being provided with a bent lock member adapted to be placed between a swinging member and stationary support for retaining the receiver box in predetermined position, a member movably mounted in the receiver box and normally cooperating with said rod to prevent the engagement of said catch device therewith, and a platform in operative connection with said member and upon which articles placed in the receiver box are adapted to rest, and the placement of an article upon said platform serving to move said member into an inoperative position.

5. A receiver box of the class described provided with a closure having a catch device, a rod mounted transversely of the receiver box and in connection with which said catch device is adapted to operate, said rod projecting through one side of the receiver box and being provided with a bent lock member adapted to be placed between a swinging member and stationary support for retaining the receiver box in predetermined position, a member movably mounted in the receiver box and normally cooperating with said rod to prevent the engagement of said catch device therewith, and a platform in operative connection with said mem-

ber and upon which articles placed in the receiver box are adapted to rest, and the placement of an article upon said platform serving to move said member into an inoperative position, said member and platform being 70 removably mounted in said receiver box.

6. A receiver box of the class described provided with a closure having a catch device, a rod mounted transversely of the receiver box and in connection with which said catch device is adapted to operate, said rod projecting through one side of the receiver box and being provided with a bent lock member adapted to be placed between a swinging member and stationary support for retaining the receiver box in predetermined position, a member movably mounted in the receiver box and normally cooperating with said rod to prevent the engagement 85 of said catch device therewith, a platform in operative connection with said member and upon which articles placed in the receiver box are adapted to rest, and the placement of an article upon said platform serving 90 to move said member into an inoperative position, said member and platform being removably mounted in said receiver box, and the top of said receiver box being provided with a shield enclosing the lock mechanism 95 therein.

7. A receiver box of the class described provided with a closure having a catch device, a rod mounted transversely of the receiver box and in connection with which 100 said catch device is adapted to operate, said rod projecting through one side of the receiver box and being provided with a bent lock member adapted to be placed between a swinging member and stationary support 105 for retaining the receiver box in predetermined position, a member movably mounted in the receiver box and normally cooperating with said rod to prevent the engagement of said catch device therewith, a platform in 110 operative connection with said member and upon which articles placed in the receiver box are adapted to rest, and the placement of an article upon said platform serving to move said member into an inoperative position, said member and platform being 115 removably mounted in said receiver box, and the opposite sides of the receiver box being provided in juxtaposition to said rod with keepers involving spring devices for retaining the rod and the lock mechanism thereof in predetermined positions.

8. A receiver box of the class described provided with a closure having a catch device, a rod mounted transversely of the receiver box and in connection with which said catch device is adapted to operate, said rod projecting through one side of the receiver box and being provided with a bent lock member adapted to be placed between 125 a swinging member and stationary support 130 for retaining the receiver box in predetermined position, a member movably mounted in the receiver box and normally cooperating with said rod to prevent the engagement of said catch device therewith, and a platform in operative connection with said mem-

- a swinging member and stationary support for retaining the receiver box in predetermined position, a member movably mounted in the receiver box and normally cooperating with said rod to prevent the engagement of said catch device therewith, a platform in operative connection with said member and upon which articles placed in the receiver box are adapted to rest, and the placement of an article upon said platform serving to move said member into an inoperative position, said member and platform being removably mounted in said receiver box, and the opposite sides of the receiver box being provided in juxtaposition to said rod with keepers involving spring devices for retaining the rod and the lock mechanism thereof in predetermined positions, and a retaining member adapted to be mounted in connection with one side of the receiver box and to be placed between the swinging member and stationary support.
9. A receiver box of the class described provided with a closure having a catch device, a rod mounted transversely of the receiver box and in connection with which said catch device is adapted to operate, said rod projecting through one side of the receiver box and being provided with a bent lock member adapted to be placed between a swinging member and stationary support for retaining the receiver box in predetermined position, a member movably mounted in the receiver box and normally cooperating with said rod to prevent the engagement of said catch device therewith, a platform in operative connection with said member and upon which articles placed in the receiver box are adapted to rest, and the placement of an article upon said platform serving to move said member into an inoperative position, said member and platform being removably mounted in said receiver box, and the opposite sides of the receiver box being provided in juxtaposition to said rod with keepers involving spring devices for retaining the rod and the lock mechanism thereof in predetermined positions, a retaining member adapted to be mounted in connection with one side of the receiver box and to be placed between the swinging member and stationary support, and the bottom of said receiver box being of less transverse dimensions than the top thereof.
10. A receiver box of the class described provided with a closure member and a lock mechanism for said closure member, said lock mechanism being provided with a part adapted to be placed between a stationary body and movable member when the member is in its closed position for retaining the lock mechanism in its operative position, the other part of said lock mechanism being carried by said closure member and cooper-
erating with said first named part, and a unit movably mounted in the receiver box and normally cooperating with said first named part to prevent the interlocking of the separate parts of the lock mechanism.
11. A receiver box of the class described provided with a closure member and a lock mechanism for said closure member, said lock mechanism being provided with a part adapted to be placed between a stationary body and movable member when the member is in its closed position for retaining the lock mechanism in its operative position, the other part of said lock mechanism being carried by said closure member and cooper-
erating with said first named part, and a unit movably mounted in the receiver box and normally cooperating with said first named part to prevent the interlocking of the separate parts of the lock mechanism, said unit involving a platform suspended in the receiver box and upon which the articles placed therein are adapted to rest.
12. A receiver box of the class described provided with a closure member and a lock mechanism for said closure member, said lock mechanism being provided with a part adapted to be placed between a stationary body and movable member when the member is in its closed position for retaining the lock mechanism in its operative position, the other part of said lock mechanism being carried by said closure member and cooper-
erating with said first named part, a unit movably mounted in the receiver box and normally cooperating with said first named part to prevent the interlocking of the separate parts of the lock mechanism, said unit involving a platform suspended in the receiver box and upon which the articles placed therein are adapted to rest, and a member automatically actuated by the depression of said platform.
13. A receiver box of the class described provided with a closure member, a lock mechanism for said closure member comprising a part carried by said closure member and a part mounted in the receiver box, a platform movably suspended in the receiver box and upon which articles placed in said box are adapted to rest, and a U-shaped lever in operative engagement with said platform and adapted to cooperate with the last named part of the lock mechanism to automatically control the movement of the closure member into a closed and locked position.
14. A receiver box of the class described provided with a closure member, a lock mechanism for said closure member comprising a part carried by said closure member and a part mounted in the receiver box, a platform movably suspended in the receiver box and upon which articles placed in

said box are adapted to rest, a U-shaped lever in operative engagement with said platform and adapted to cooperate with the last named part of the lock mechanism to automatically control the movement of the closure member into a closed and locked position, and means for supporting the second

named part of the lock mechanism in predetermined position in the receiver box.

In testimony that I claim the foregoing ¹⁰ as my invention I have signed my name this 23rd day of Feb. 1923.

LOUIS WILKE.
